[57] **CLAIM**

The ornamental design for a tire for a vehicle wheel, as shown and described.

DESCRIPTION

FIG. 1 is a perspective view of a tire for a vehicle wheel showing my new design, it being understood that the tread design is repeated throughout the circumference of the tire, the opposite side being the same as that shown;

FIG. 2 is an enlarged fragmentary elevational view thereof;

FIG. 3 is a side elevational view thereof.
